Primary Examiner — Jonathan J Han(74) *Attorney, Agent, or Firm* — Marshall A. Lerner; Steven J. Kim; Kleinberg & Lerner, LLP(57) **CLAIM**

The ornamental design for a shoe as shown and described.

DESCRIPTION

FIG. 1 is a perspective view of a shoe in accordance with my new design;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The dash-dash broken lines and the areas within the broken lines represent portions of the shoe that form no part of the claimed design.

1 Claim, 7 Drawing Sheets(56)
